UNITED STATES PATENT OFFICE.

MABEL WATERMAN, OF NEW ROCHELLE, NEW YORK.

DESIGN FOR A TOY RABBIT KNOWN AS PETER BUNNY.

58,413.

Specification for Design.

Patented July 12, 1921.

Application filed February 19, 1920. Serial No. 359,938. Term of patent 14 years.

To all whom it may concern:

Be it known that I, MABEL WATERMAN, a citizen of the United States, and a resident of New Rochelle, in the county of Westchester and State of New York, have invented a new, original, and ornamental Design for a Toy Rabbit Known as Peter Bunny, of which the following is a specification, reference being had to the accompanying drawing, forming a part thereof.

Fig. 2 is a side elevation of the toy rabbit known as Peter Bunny;

Fig. 3 is a front elevation of the toy rabbit known as Peter Bunny in a different posture; and

Fig. 4 is a side elevation of the toy rabbit known as Peter Bunny in the same posture as Fig. 3.

I claim:—

The ornamental design for a toy rabbit known as Peter Bunny as shown.

MABEL WATERMAN.
